UNITED STATES PATENT OFFICE

PAUL VENAIL, OF PARIS, FRANCE, ASSIGNOR TO SOCIETE ANONYME DE FABRICATION
DES TAPIS A POINTS NOUVEAUX "SAFTAN", OF PARIS, FRANCE

LOOM FOR THE MANUFACTURE OF PILE FABRICS

Application filed December 12, 1927, Serial No. 239,558, and in France August 25, 1927.

The present invention relates to the manufacture of pile fabrics, more particularly to Persian, Smyrna, wound or other knot-stitch carpets, by means of the known types 5 of carpet looms in which warp selecting means and tuft yarn inserters or needles are used for winding the tufts around the warps selected in groups.

In looms of these types, for making carpets with wound knots, all the threads of the warp sheet, are selected, that is to say, before the passage of the tuft-yarn inserters or needles through the warp sheet, all the warp threads are grouped two by two in variable 15 alternate order so as to leave spaces between them for the passage of the tuft-yarn inserters in order to wind the tufts around each group of warp threads so as to produce the knots.

20 The groups of threads are formed alternately by selecting means, usually an alternately longitudinally displaced set of toothed combs, whereby each warp thread of the warp sheet, is grouped alternately with the adjacent thread from the right and with that from the left.

In order that the knots may be produced by surrounding the groups of threads in looms of this type, it is necessary that the 25 tuft-inserters or needles which carry the tufts for making these knots, pass between the warp threads alternately on the right and on the left of the group of selected threads and between the two threads of a group, according to an order which may vary according to the kind of knot to be produced.

30 In order that these tuft-yarn inserters or needles may thus pass successively on each side of the group and between the threads of said group, so as to surround them with the tufts which they carry, it is necessary either to displace alternately and laterally the groups of selected threads relatively to the alternative rectilinear course of the needles or 35 to displace alternately and laterally the needles before they have passed between the groups of warp threads, the warp sheet remaining stationary.

To that effect, the looms above referred to 40 are of two types:

The first known type of looms consists in displacing the whole system of warp threads, laterally and alternately, it being understood that by the term "whole system of the warp threads" is meant the upper roller for delivering warp, the lower drum for winding on the carpet in proportion to its manufacture, the boxes or frames supporting this unit which is heavy and costly, and which requires a suitable mechanism complicated to actuate, 55 for ensuring for the said unit an alternate transverse displacement.

In this first type of looms, the tuft-yarn inserters or needles are actuated with their alternate longitudinal movement.

60 The second known type of looms, wherein the whole system of the warp sheet remains stationary, consists in displacing the whole system of the tuft-yarn inserters or needles alternately and laterally before being passed through the warp sheet according to their alternate longitudinal movement, it being understood that by the term "whole system of the tuft-yarn inserters" is meant the tuft-yarn inserter carriers, the carriages for said carriers, the frame for supporting said carriages, this unit being heavy and costly, and requiring a complicated mechanism to actuate it for ensuring for the said unit an alternate transverse displacement.

65 The object of the present invention is to render the operation of winding the tufts around the groups of selected warp less complicated and less costly to carry out, and this object is attained by performing this operation according to a new method. The looms which are adapted or constructed to work according to said improved method may be regarded as constituting a third type of looms 70 for the manufacture of pile fabrics, more particularly for Persian, Smyrna, wound or other knot-stitch carpets.

75 This method consists in maintaining the whole system of the warp threads as well as the whole system of tuft-yarn inserters stationary, without alternate transverse movements, during the production of the knots, while the necessary alternate transverse movements of the grouped selected warp threads are effected by means of the select- 80

ing means, to which alternate transverse supplemental motion is imparted.

This method, when applied to looms of the above mentioned types, proves to be a very important advancement in that, when applied to known looms of the first type, the whole system of moving the warp sheet transversely is dispensed with, and when it is applied to looms of the second type, the whole system of moving the tuft-yarn inserters or needles is dispensed with.

Moreover the improved method, when applied to newly constructed looms, dispenses with the application of any system for displacing laterally either the whole of the warp sheet or the whole of the tuft-yarn inserters.

Therefore, to carry out said method, when applied, either to looms of the known types, or to looms newly constructed, whatever may be the selecting means or systems fitted on said known looms or proposed to be fitted on said newly constructed looms, it is only necessary to modify or to construct said selecting means, so that to the ordinary motion imparted to them in order to effect the alternate grouping of the selected warps, a supplemental motion is imparted to them, (after the warp threads have been selected in groups and before the tuft-yarn inserters are passed through the warp sheet) to the effect that said selecting means is moved alternately and laterally.

By way of example, the invention is shown applied to the selecting means of the loom described in my prior U. S. Patent 1,690,802, which relates to a loom of the second type. In the accompany drawing:

Fig. 1 is a side elevation showing the reed or batten and the selecting combs of the selecting system, modified and fitted to be capable of being alternately and laterally displaced with regard to the remaining parts of said system which are only capable of a to-and-fro longitudinally oscillating movement.

Fig. 2 is a front view showing one end of the reed and selecting combs and means for imparting to them the required alternate lateral movement.

Fig. 3 is an enlarged perspective view, partly in section, of the reed and selecting combs.

Figs. 4, 5 and 6 are enlarged details showing the various positions of the reed and selecting combs and corresponding groupings of the warp threads.

Referring to the drawing in detail, 1 indicates the frame oscillating longitudinally and descending in accordance with my prior patent above referred to. A reed or batten 2 is provided with guides 4 adapted to slide transversely in the frame 1 and carries the selecting combs 3-3 which latter are fixed to the inside of the reed or batten.

Several of the threads of the warp sheets extending vertically and across the width of the loom are indicated at a, b, c, d and e, a

warp thread passing between each two adjacent members of the reed 2. Two consecutive threads are alternately lodged and "wedged" into one tooth of each selecting comb 3 as the latter comes alternately in contact with the warp sheet when oscillated.

The alternate lateral displacement of the reed and combs 2 and 3 with the selected group of threads is effected by anti-friction rollers 5 carried at the ends of the guides 4 and coacting with a cam 6 mounted on a shaft 7, the latter being actuated from the loom through a link lever 8, it being understood that the actuation of the slideable reed and combs 2, 3 takes place only when the selecting system reaches the end of its oscillatory movement. The combs 3 are then in a position for selecting the threads for allowing the passage of the tuft-yarn inserters. It will also be understood that each time the unit constituted by the parts 1, 2, 3 and 4 oscillates either toward the front or the rear of the loom, the grouping or selection of threads varies in accordance with the positions illustrated in Figs. 4-6.

In Fig. 4 a grouping of threads is shown in which the thread a stands alone, the threads b-c and d-e being grouped or selected. The tuft-yarn inserter or needle indicated at p, having longitudinal reciprocating movement passes only between the groups b-c and d-e.

The selecting system or unit constituted by the parts 1, 2, 3 and 4 being oscillated, the opposite set of teeth 3 group the threads in the order a-b and c-d, with the threads e standing alone, as shown in Fig. 5. If at this moment the reed 2 and the teeth 3 are displaced as a unit towards the right (Fig. 5) the tuft inserter p will pass between the groups a-b and c-d. When the reed 2 and teeth 3 are displaced to the left as shown in Fig. 6 the tuft inserter will pass between the group c-d and the thread e, in the case that the thread e is the last thread of the warp sheet. Thus, during the alternate passages or courses of the inserters p, the tuft yarn is wound about the threads c-d and between them for producing a stitch knot.

What I claim is:

1. In a loom for the manufacture of pile fabric more particularly oriental, Persian, wound and other knot-stitch carpets of the kind referred to, the combination of a batten, two selector combs associated with said batten to move therewith and means for reciprocating said batten and selector combs transversely to the warp threads for the purpose of imparting transverse movement to selected warp threads, substantially as described.

2. In a carpet loom of the type referred to having reciprocating tuft yarn inserters moving constantly in the same planes, the combination of a frame adapted to move up and down and to turn about a horizontal axis,

a batten and two selector combs slidably mounted in said frame to move transversely with regard to the warp threads, and means for reciprocating said batten and selector 5 combs in said frame when said frame is in the highest position, substantially as described.

3. A method for the manufacture of pile fabrics with oriental, Persian, wound and other knot-stitch, on looms having tuft-yarn 10 inserters, consisting in maintaining the whole system of the warped threads as well as the whole system of tuft-yarn inserters stationary without alternate transverse movements, during the production of the knots, while the 15 necessary alternate transverse movements of the selected warp threads are effected by means of the selecting means, to which an alternate transverse motion is imparted.

In testimony whereof I affix my signature.
